UNITED STATES PATENT OFFICE.

ROBERT E. GREEN, OF NEW YORK, N. Y.

AIRSHIP.

960,539.

Specification of Letters Patent. Patented June 7, 1910.

Application filed June 22, 1909. Serial No. 503,654.

To all whom it may concern:

Be it known that I, ROBERT E. GREEN, a citizen of the United States, and a resident of New York, county and State of New

5 York, have invented certain new and useful Improvements in Airships, of which the following is a full, clear, and exact description.

This invention relates more particularly to what are known as aeroplanes or heavier-10 than-air airships.

The primary object of the invention is to provide a simple and efficient machine in which a very large sail or supporting area may be contained in a compact space, and 15 the sails or supporting elements made adjustable so that the machine may be properly manipulated in its flight either for ascending or descending or for sailing in a direct line, thereby overcoming the objections of machines of this character as ordinarily constructed in which the parts thereof project a considerable distance from the body of the machine to give a proper supporting surface and which parts are likely to become damaged or injured and which make the machine 20 cumbersome and not easily handled.

Other objects of the invention are to provide propelling means so positioned with relation to the sail or elements forming the 25 supporting means, that the air through the rotation of the propeller or propellers will be caused to come in contact with the sails and thereby materially assist in the lifting power, so that it will not be necessary for 30 the machine to travel as fast to secure the proper effect of the air on the sails, and as the speed of the machine increases, the sails may be adjusted so that the said machine may glide swiftly through the air with very 35 little resistance; to provide means whereby the sail area both at the back and at the front of the propelling means may be substantially the same so that the lifting effect 40 will be substantially equal; and to so construct the machine that the weight will be below the supporting elements and substantially centrally thereof in order that proper 45 steadiness and equilibrium may be properly sustained.

50 Another object of the invention is to provide simple and efficient means whereby suitable rudders may be operated to steer the machine, and the said rudders so positioned that they are not likely to be injured.

55 A further object of the invention is to provide simple operating mechanism for the

several parts of the machine, and to so construct the machine that the same will be very light and at the same time very strong and effective in use.

With these and other objects in view, the invention will be hereinafter more particularly described with reference to the accompanying drawings which form a part of this specification, and will then be pointed out in 60 the claims at the end of the description.

In the drawings, Figure 1 is a side elevation of one form of machine embodying my invention. Fig. 2 is a vertical section taken on the line II—II of Fig. 1. Fig. 3 is a 70 fragmentary sectional plan, taken on the line III—III, showing the rudder and means for operating the same. Fig. 4 shows how the sails or supporting elements may be made hollow to be filled with gas to assist 75 in the lifting power; and Fig. 5 shows how the sails may be curved to give a greater area in a given space.

The frame 10 may be of any suitable construction and arranged in any desired way. 80 As shown it is substantially rectangular being provided with the uprights 11 at the front of the machine, and uprights 12 at the rear of the machine, and these uprights may be arranged in pairs and are connected 85 and rigidly held by the longitudinally-extending bars or beams 13, and the transversely-extending beams 14, and underneath the transversely-extending beams is a cage or other part 15 serving as a place for the 90 operator who is to manipulate the machine and also for one or more passengers if desired. The cage or body 15 may be partly or wholly closed and is located under the frame substantially centrally of the machine, so that the weight placed therein will 95 be properly distributed with respect to the other parts of the machine.

A plurality of sails 16 are arranged at the front of the machine, and a plurality of 100 sails 17 at the rear of the machine. These sails or supporting elements are arranged in sets and may be substantially rectangular in form. Each sail has a substantially plane surface and may be constructed with a 105 frame having a cloth or other body secured to said frame or otherwise made as desired, and the sails or elements 16 are pivotally held, at 18, between the uprights 11 of the frame, and the sails or elements 17 are pivotally held, at 19, between the uprights 12 at the rear of the machine frame. The set 110

or group of sails 16 and the set of sails 17 may be moved together either upward or downward, so that proper resistance may be offered to the air in order to cause the machine to rise or lower in its flight, though, of course, each set of sails may be independently operated in case it is desired to do so. Each of the sails 16 is secured to a movable element or connection at the rear thereof so that all of the sails 16 will be moved in unison, and said element or connection may be in the form of a cable, chain or other means, or eyes may be provided, as 21, connected together by links 22, and to the outer sails may be connected a flexible connection 23, one end of which is fastened to the upper sail of the set 16 and is adapted to pass about a pulley 24 to and around an idler 25 under the lower beam or bar 14, and around an operating drum 26 located within the cage or body 15, and the lower sail is connected to the other end of said connection 23. This drum may be provided with a worm gear 27 which is engaged by a worm 28, and said worm is operated by a rod 29 to move the drum and thereby adjust the sails 16 either upward or downward according to the direction of movement of said drum. The sails 17 are similarly held to move in unison, and as shown are so connected to the drum 26 that they incline or adjust themselves in the same direction and simultaneously with the movement of the sails 16. These sails 17 are connected together by the links 30, and through a flexible connection 31 which passes about a pulley 32 at the upper part of the frame and around the drum 26 to be operated thereby at the same time that the sails 16 are adjusted.

The group of sails 16 and 17 are spaced apart, as at 33, and in said space substantially centrally of the machine, is arranged one or more propellers 34. The propelling means is mounted on a shaft 35, and this shaft may be rotated by a chain 36 operatively connected to a suitable motor 37, as a gasolene or any other motor, so that as the said motor is operated, it will rotate the propeller or propellers and cause the air to be drawn under the sails 16 and forced back under the group of sails 17, to increase the lifting force of the sails 17 owing to the air being forced under said sails, thus over-coming the necessity for the high speed of a machine of this character in order to get the proper supporting effect of the air to sustain the machine.

To properly steer the machine, various means and arrangement of devices may be employed. As shown, I provide a rudder 38 comprising two members 39 and 40 which are pivotally held at 41 at the lower part and at the rear of the machine in the space between the lower sails or elements, and con-

nected to the rudders so as to shift the same laterally in a horizontal plane is a rope or other connection 42. This rope or connection 42 is held to the rudders or steering means substantially at the center or pivot of the sails 17 to which the rudders are held and with which the rudders move, so that very little movement is given to the connection 42 should the sails 17 be adjusted upward or downward. The flexible connection 42 is secured at its ends to opposite sides of the lower member 39, and one end of the connection passes around pulleys 43 on one side of the machine, and around pulleys 44 at the other side of the machine, and said connection then passes around idlers 45 and 46 to a drum 47. This drum may have a worm gear formed as a part thereof which may be operated by a worm 48 located within convenient reach of the operator, so that as said drum is rotated, it will move the steering rudders laterally according to the direction of rotation of said drum, though the steering means, as well as the adjusting means for the sails, may be of any suitable construction.

The cage 15 may be provided with a seat 49 for the operator and one or more seats 50 for a passenger or passengers, and as will be seen the motor and mechanism is disposed substantially centrally of the machine and under the sails so that in case of accident, the sails may be made to act in substantially the same manner as a parachute, and should the machine fall from accident or otherwise, the machine or occupants thereof are not likely to be injured.

In Fig. 4 is shown a construction whereby each sail or supporting element may be made hollow. The frame of the element or sail 51 may be suitably braced and may be covered by fabric or otherwise, and the space within the sail may be filled with gas in order to assist in supporting the machine, and said device may be pointed, as at 52, both at the rear and front thereof to offer as little resistance as possible to the air.

In Fig. 5, the sail or supporting element instead of being made straight, may be curved transversely of the machine so that the surface area of the sail may be somewhat greater without being any wider, and in this case the sails may be connected together in sets and may be pivotally held to the machine frame as already described.

It will be understood that the sails may vary in size, that is each sail may be narrower than the one above throughout the entire series, so that a better effect on the air may be obtained, and particularly when lowering, as each sail at its edges will extend beyond the one below and will thereby have a parachute effect on the air.

From the foregoing it will be seen that a simple and efficient machine is provided in

which a large supporting area is located within a compact space; that said machine has a number of superposed supporting elements or sails so arranged that they may be 5 adjusted together and thereby properly control the machine in its flight; that the weight of the machine is so distributed that it is substantially balanced so that it is not likely to turn over in case it should fall through 10 accident or otherwise; that said machine has its propelling means so arranged that it will assist in supporting the machine in its flight through the air; and that simple means is provided for steering the machine and which 15 is so arranged that the said steering means is not likely to be injured while in use.

Having thus described my invention, I claim as new and desire to secure by Letters Patent:—

20 1. In an aeroplane, the combination with a frame, of a set of horizontally arranged and superposed sails located at the forward part thereof and pivotally held to the frame, a set of horizontally arranged and superposed sails pivotally held at the rear of the machine and separated from the first-mentioned sails, means for moving the sets of sails in unison, propelling means arranged between the sets of sails so as to force the air 25 under the sails at the rear of the machine, steering means carried by the rear set of sails, and means for laterally moving said steering means.

2. In an aeroplane, the combination with 30 a frame, of a set of superposed and horizontally arranged sails located at the forward part thereof and pivotally held to the frame, a set of horizontally arranged sails pivotally held at the rear of the machine and separate 35 40 from the first-mentioned sails, means for

moving the sets of sails, propelling means arranged between the sets of sails, steering rudders carried by the rear set of sails, and means for laterally moving said rudders.

3. In an aeroplane, the combination with 45 a frame, of a plurality of sails located at the forward and rear parts thereof, means for moving the sails, and rudders carried by the rear sails, and means for laterally moving said rudders.

4. The combination with a plurality of horizontally arranged and pivotally held sails located at the front and rear of the machine, of steering means pivotally supported to move laterally on the rear sails, and means 50 55 for operating said steering means.

5. In an aeroplane, the combination with a frame, of two sets of sails, means for pivotally holding said sails, means for moving said sails in unison, propelling means, a cage 60 located under the frame substantially centrally of the machine, means located within the cage for operating said propelling means, and steering means pivotally supported to move laterally on said sails.

6. In an aeroplane, the combination with a frame, of two sets of sails, means for pivotally holding said sails, propelling means, a cage located under the frame substantially centrally of the machine, means for operating 70 said propelling means, and steering means pivotally supported to move laterally on said sails.

This specification signed and witnessed this 19th day of June A. D. 1909.
